CLARENCE L. SHIVERS, OF ST. LOUIS, MISSOURI, ASSIGNOR OF ONE-FOURTH TO GRANVILLE HOGAN AND ONE-FOURTH TO FRANK Y. GLADNEY, BOTH OF ST. LOUIS, MISSOURI.

MEANS FOR SUPPLYING A COMBUSTIBLE MIXTURE TO INTERNAL-COMBUSTION ENGINES.

1,202,111.

Specification of Letters Patent.

Patented Oct. 24, 1916.

Application filed January 30, 1914. Serial No. 815,341.

To all whom it may concern:

Be it known that I, CLARENCE L. SHIVERS, a citizen of the United States, residing in the city of St. Louis and State of Missouri, 5 have invented new and useful Improvements in Means for Supplying a Combustible Mixture to Internal-Combustion Engines, of which the following is a specification.

This invention relates to means for supplying a combustible mixture to internal combustion engines.

It has for its principal objects the utilization of the gas which accumulates in the supply tank above the body of gasoline 15 therein; to effect a saving in the gasoline supply; and to attain certain other advantages which will hereinafter more fully appear.

The invention is adapted more particularly for use in motor vehicles and the like, but it is not limited to such use.

It consists in the parts and in the arrangements and combinations of parts hereinafter described and claimed.

25 In the drawing Figure 1 is a fragmentary view, partly in side elevation and partly in section, of a portion of an automobile equipped with a device embodying the invention; Fig. 2 is a section on an enlarged 30 scale of the valved box which controls the supply of the combustible mixture to the intake manifold of the engine; Fig. 3 is a section on the line 3—3 of Fig. 2; Fig. 4 is a detail view of the coupling between the supply tank and conducting pipe; and Fig. 5 is a detail view of the air intake collar for the tank.

In the drawing, 1 represents an ordinary supporting frame or chassis of an automobile on which is mounted the body 2 and internal combustion engine 3. As shown, the engine is of the four cylinder type, and it is provided with an intake manifold 4 having branches 5 through which the combustible mixture is supplied to the respective cylinders. Attached to the end of the manifold is an ordinary carbureter 6 which is connected by a pipe 7 with a gravity feed gasoline supply tank 8, which latter is located 45 under the front seat 9 of the automobile. The engine is also provided with an exhaust manifold 10 having branches 11 which communicate with the respective cylinders, said

manifold having a pipe extension 12 extending downward and rearward under the body 55 of the automobile, as is the usual practice.

At the top of the gasoline supply tank 8 is a nipple 13 to which is attached an elbow coupling 14. From this elbow coupling leads a pipe 15 which is connected to a 60 valved box or chamber 16, said box being attached to the intake manifold 4 between the branches 5 thereof and the carbureter 6, and the pipe 15 being coiled around the exhaust manifold 10.

As shown in the drawing, the box 16 is made in two sections 17, 18, and secured together by a screw threaded engagement. A partition plate 19 is secured between the two sections. This plate is provided with a series of perforations 20, and co-operating therewith is a rotary disk 21 having perforations 22 therein adapted to register with said perforations 20. This disk is provided with a central stem 23 which extends 70 through a tubular projection 24 on the inside of the section 18; and said stem 23 is provided on its end, outside of the box, with a lever arm 25 by which the disk may be rotated.

80 In the section 17 is a disk check-valve 26 which is yieldingly held against the partition plate 19 by a spring 27. As shown, the check-valve 26 is provided with a tubular stem 28 which works over a guide pin or 85 stem 29 provided on a plate 30, which latter is secured to a perforated or gauze strainer 31 which is secured at its margin to the section 17. Preferably this strainer is conoidal, and arranged with its apex toward the 90 partition 19. It is also preferable to place a strainer 31a within the section 18 between the inlet opening 32 and said partition plate 19. As shown, the inlet opening is at the side of the box, while the outlet opening is 95 through a nipple 33 at the end of the housing. This arrangement of the respective openings may be modified or changed to suit different conditions in the application of the invention to engine structures of different 100 types.

At the top of the gasoline tank 8 is an air inlet collar 34 which may be applied to the filler opening in place of the usual closure therefor. This collar is provided with 105 a strainer 35 to prevent the entrance of

dust or grit. Below this strainer is a spiral 36 which prevents the gasolene from splashing out of the tank. The spiral also causes the air which is taken into the tank to travel 5 in a swirling motion whereby it more readily commingles with the gas in the tank. It is also preferable to provide a spiral 37 in the nipple 13 to prevent the splashing gasolene from entering the coupling member 14; and 10 said coupling member 14 is preferably provided with a strainer 38.

As shown in the drawing, the throttle between the carburetor and the intake manifold is operated by a rod 39 which is connected to a foot lever 40 adjacent to the dash board. However, the throttle may be 15 operated in any desirable manner. The rotary valve member 21 in the box 16 may be operated through the medium of any desirable 20 device. As shown, a small tube 41 is fastened along the steering column 42, and extended in proximity to the box 16 where it is attached to a supporting arm 43. A relatively stiff wire 44 is slipped through 25 this tube 41, and it is secured at one end to said lever arm 25 and at its opposite end to an operating lever or handle 45 which is mounted on the steering post in proximity to the steering wheel 46.

30 The constant shaking or agitation of the gasolene in the tank 8 while the automobile is in motion causes an accumulation of vapor in the top of the tank so that after the engine is well started the supply of gasolene 35 to the carburetor may be reduced considerably, and the throttle valve may be closed to a relatively small opening and the valve member 21 in the box 16 may be operated to admit the mixture of air and vapor which 40 is taken from the top of the tank 8 direct into the manifold 4 above the throttle valve, thus utilizing in doing useful work the gaseous vapors which are usually wasted through the vent opening, or which remain dormant 45 in the tank above the body of gasolene. By the application of this auxiliary gas supply to the motor an increased mileage is obtained from a given quantity of gasolene. In some cases, the mixture from the top of 50 the tank 8 is used to augment the mixture from the carburetor, while in other cases the supply through the carburetor may be entirely cut off, depending upon weather conditions and the desired richness of the explosive charge.

Obviously the apparatus admits of considerable modification without departing from the spirit of the invention. Therefore, I do not wish to be limited to the specific instruction and arrangement shown.

I claim:

1. The combination of a supply tank containing a hydrocarbon liquid, said tank having an air inlet, a carburetor, means for 65 conducting the liquid from said supply

tank to said carburetor, a pipe for conducting the combustible mixture from said carburetor, means for controlling the communication between said carburetor and said conducting pipe, a pipe connected to said supply tank above the body of liquid therein and communicating with said conducting pipe for the combustible mixture from said carburetor, and means for controlling the flow through said pipe leading from the top 75 of the supply tank, whereby the combustible mixture from said carburetor and the gas from said supply tank may be supplied either separately or conjointly to the conducting pipe from said carburetor at will. 80

2. The means for supplying fuel to an internal combustion engine, comprising a gasolene supply tank, a carburetor, a pipe connection for conducting the gasolene to said carburetor from said supply tank, a 85 pipe connection from said carburetor to the combustion chamber of the engine, a throttle valve for controlling the passage of the combustible mixture through said second mentioned pipe connection, a valve 90 box communicating with said second mentioned pipe connection, a valve in said box for controlling the flow therethrough, a check-valve coöperating with said controlling valve, and a pipe connection between 95 said box and said gasolene supply tank above the body of gasolene therein.

3. The means for supplying fuel to an internal combustion engine, comprising a supply tank containing a hydrocarbon 100 liquid, said tank having an air inlet above the body of liquid therein, a carburetor, means for conducting the liquid from said tank to said carburetor, means for conducting the combustible mixture from said carburetor to the combustion chamber of the 105 engine, and a pipe connected to said tank above the body of liquid therein and communicating with the combustion chamber of the engine. 110

4. The means for supplying fuel to an internal combustion engine, comprising a supply tank containing a hydrocarbon liquid and having an open air inlet above said liquid, a carburetor, means for conducting the hydrocarbon liquid to the carburetor, means for conducting and controlling the mixture from the carburetor to the engine, and means for conducting and controlling a mixture of air and vapor from above the 115 body of the liquid in the tank to the engine. 120

5. The means for supplying fuel to an internal combustion engine, comprising a supply tank containing a hydrocarbon liquid, 125 said tank having an air inlet, a carburetor, means for conducting the liquid from said tank to said carburetor, means for conducting the combustible mixture from said carburetor to the combustion chamber of the 130

- engine, means for conducting the gas in said supply tank from above the liquid therein to the combustion chamber of the engine, and controlling means whereby the combustible mixture from the carbureter and the gas from the supply tank may be supplied either separately or conjointly to the engine at will.
6. The means for supplying fuel to an internal combustion engine, comprising a supply tank containing a hydrocarbon liquid, said tank having an open air inlet above the body of liquid therein, a carbureter communicating with the intake for the combustible mixture to the engine, means for conducting the hydrocarbon liquid from said tank to said carbureter, a valve box communicating with the intake for the combustible mixture to the engine intermediate said carbureter and the engine, said valve box having a perforated partition, a perforated rotary disk coöperating with said partition for controlling the flow through the box, means for turning said disk, a check-valve in said box, and a pipe connection between said box and said supply tank above the body of hydrocarbon liquid therein.
7. In an apparatus of the character described, a supply tank having a tortuous air inlet collar at the top thereof and above the
- body of liquid therein, said collar having a tortuous passageway therethrough, said tank also having a tortuous outlet collar at the top thereof, and a conducting pipe connected to said outlet collar and arranged and adapted for communication with the fuel intake of an internal combustion engine or the like.
8. The combination with an ordinary fuel supply apparatus for internal combustion engines and the like, comprising a gravity feed supply tank containing a hydrocarbon liquid, a carbureter, means for conducting the liquid from said tank to said carbureter, and means for conducting and controlling the combustible mixture from said carbureter to the fuel intake of the engine, of a pipe connected at one end to said supply tank above the body of the liquid therein and communicating at its opposite end with the fuel intake of the engine, and means for controlling the flow through said pipe.

In testimony whereof, I have hereunto set my hand in presence of two subscribing witnesses.

CLARENCE L. SHIVERS.
